DESCRIPTION

(52) **U.S. Cl.**

USPC **D6/559**

(58) **Field of Classification Search**

FIG. 1 is a perspective view from the front of a cupboard embodying my design.

USPC D9/559; D6/329, 512, 552, 553, 666;

FIG. 2 is a front elevational view thereof.

D12/345; D19/75; D14/440

FIG. 3 is a rear elevational view thereof.

CPC A47B 49/006; A47B 47/03; A47B 81/002;

FIG. 4 is a top plan view thereof.

A47B 95/008; A47B 43/00; A47B 46/00;

FIG. 5 is a bottom plan view thereof.

A47B 47/04; A47B 67/00; A47B 77/00;

FIG. 6 is a right side elevational view thereof; and,

A47G 29/08

FIG. 7 is a left side elevational view thereof.

See application file for complete search history.

The broken lines in FIG. 3 are included for the purpose of illustrating portions of the design that form no part of the claimed design.
